DOOR HANDLE ASSEMBLY

William C. Devereaux, Detroit, Mich.

Application September 19, 1938, Serial No. 230,702

11 Claims. (Cl. 292—359)

This invention deals with door handle assemblies and more especially door handle assemblies having provision for locking the door handle shank firmly in place in the body of the door.

5 One of the objects of this invention is to provide a door handle structure composed of a plurality of parts capable of being readily assembled and locked in place in the door. A further object of this invention is to provide a door handle assembly having a positive locking means for the handle of a simple and inexpensive design.

With these and other objects in view, the invention resides in certain novel features of construction, combinations and arrangements of parts as 15 will be more fully described and particularly pointed out in the appended claims.

With reference to the drawing:

Figure 1 is a top plan view of the invention with the door sectioned away;

20 Figure 2 is a sectional view of the mounting cup taken along the lines 2—2 of Figure 1;

Figure 3 is a sectional view taken along the lines 3—3 of Figure 2;

25 Figure 4 is a sectional view showing the method of removing the door handle;

Figure 5 is a view similar to Figure 1 showing a modification of the design; and,

Figure 6 is a sectional view taken along the lines 6—6 of Figure 5.

30 With reference to Figure 1, it will be seen that the invention deals with a door handle such as 10 having a shank 11 extending through the outer panel 12 of the door as well as through an escutcheon plate 13 on the exterior side of the door 12. Shank 11 extends to the inner side 35 of the door and is maintained in place through a locking clip 15 located in a mounting cup 16 preferably of sheet metal construction. The invention resides in the construction of the mounting cup and clip in a manner to firmly lock the shank 11 in place inside the door body, which 40 in turn assures proper location of the handle 10 with relation to the escutcheon plate 13 and the outer panel of the door.

45 With reference to the invention more in detail, wherein like reference characters indicate like parts, it will be seen that the door panel 12 is provided with an opening 17 through which shank 11 may pass. On the inner side of panel 50 12 and surrounding this opening is a mounting cup 16. This cup is formed from a sheet metal stamping and has attached portions 18 extending laterally therefrom to provide for attaching the cup inside of the panel 12 by welding or the like. The bottom 19 of the cup is provided with

an opening 20 in alignment with opening 17 in the door through which the shank 11 may also be extended.

The cup, as shown, is provided with an annular side wall having openings 21 in diametrically opposite sides and having lugs 22 extending inwardly therefrom between the openings 21. In the present instance the lugs are struck inwardly from the side wall of the cup. The cup is mounted on the door in a manner so as to have 10 one of the openings 21 facing the swinging edge of the door. This will place the lugs 22 at substantially right angles to the openings 21. The lugs 22 are designed so that the free edges 23 are spaced a sufficient distance from the adjacent surface 19 of the cup to allow the leg 29 of the clip 15 to slide between the edges 23 of the lugs and the surface 19 of the cup.

Shank 11 is rectangular in cross section and has one end permanently secured within the end 20 24 of the handle 10 in any suitable manner. As stated above, the shank is maintained in place 25 in the door by the spring clip 15. This clip is formed of two substantially V-shaped sheet metal members 25 and 26 identical except that the 30 dimensions are so determined as to permit nesting of the members. Both legs 28 and 29 of the clip have openings 30 therein of sufficient dimension to allow the shank to pass therethrough when the legs are compressed to dispose the 35 openings in parallel relationship to one another.

Upon reference to Figure 3 it will be noted that the diametrically opposite sides of openings 30 on the legs of the clip are fashioned to 40 form lips 45 adapted to have a biting engagement with the adjacent sides of the shank when the pressure is released from the clip and the legs returned to their normal angularly related positions. It will be noticed that by providing two V-shaped sheet metal members 25 and 26 45 instead of one that additional efficiency is created. Instead of having two sets of lips 45 effecting a biting engagement with the shank, actually there are four sets of lips. Not only is the wedging effect increased by the use of a clip 50 in two parts instead of one, but also if one of the clips fails to function properly the locking effect of the remaining clip will be present.

After the clip is initially placed on the shank, the shank is inserted into the door and rotated 55 to effect locking of the clip with the cup. This is accomplished in the present instance by providing a lower leg 29 of the clip with two notches 51 of sufficient size to allow the clip to slide over lugs 22. It will be noticed that these notches 55

handle having a shank adapted to be inserted in a door, a spring clip mounted on the shank to form a unit with the latter and frictionally secured to the shank to prevent relative axial movement between the shank and clip, and means carried by the door and cooperating with the clip to secure the shank in assembled relation with the door.

7. In a door handle assembly, an operating handle having a shank adapted to be inserted in a door, a spring clip mounted on the shank to form a unit with the latter and frictionally secured to the shank to prevent relative axial movement between the shank and clip, and means carried by the door and responsive to rocking movement of the shank and clip to engage the clip and prevent unauthorized withdrawal of the shank from the door.

8. In a door handle assembly, an operating handle having a shank adapted to be inserted in the door, a clip having a portion apertured to freely receive the shank and normally urged to a position angularly disposed with respect to a plane perpendicular to the axis of the shaft to frictionally engage opposite edges of the opening with the adjacent sides of the shank and thereby lock the shank against axial movement relative to the clip, and means carried by the door and responsive to rocking movement of the shank and clip to engage the clip and prevent withdrawal of the shank from the door.

9. In a door handle assembly, an operating handle having a shank adapted to be inserted in the door, a clip having a portion apertured to freely receive the shank and normally urged to a position angularly disposed with respect to a plane perpendicular to the axis of the shaft to

frictionally engage opposite edges of the opening with the adjacent sides of the shank and thereby lock the shank against axial movement relative to the clip, a cup-shaped member carried by the door forming a housing for the clip and having a projection responsive to rocking movement of the shank and clip to engage the clip and prevent withdrawal of the shank from the door.

10. In a door handle assembly, an operating handle having a shank adapted to be inserted in a door, a spring clip mounted on the shank to form a unit with the latter and frictionally secured to the shank to prevent relative axial movement between the shank and clip, a cup-shaped member carried by the door and adapted to house the clip, and projections on the cup-shaped member effective upon rocking movement of the shank and clip to engage said clip and prevent withdrawal of the shank from the door.

11. In a door handle assembly, an operating handle having a shank adapted to be inserted in a door, a spring clip having diverging sides provided with openings therethrough dimensioned to freely receive the shank when the sides of the clip are flexed to a position wherein said sides are substantially parallel to one another, the opening in one side having an edge portion arranged to fixedly grip the shank in the angular position of the sides to prevent relative axial movement of the shank and clip, a cup-shaped member carried by the door and adapted to house the clip, and projections on the cup-shaped member responsive to rocking movement of the shank and clip to engage one of the sides of the clip and prevent axial displacement of the shank relative to the door.

WILLIAM C. DEVEREAUX.
